UNITED STATES PATENT OFFICE.

PAUL KESTNER, OF LILLE, FRANCE.

APPARATUS FOR ATOMIZING LIQUIDS.

No. 888,091.

Specification of Letters Patent.

Patented May 19, 1908.

Application filed October 10, 1906. Serial No. 338,227.

To all whom it may concern:

Be it known that I, PAUL KESTNER, a citizen of the French Republic, residing at Lille, in the Nord Province of France, have 5 invented new and useful Improvements in Apparatus for Atomizing Liquids, of which the following is a specification.

This invention has reference to improvements in apparatus for atomizing liquids and 10 simultaneously mixing them with air or gas, and it consists essentially in an improved drum or wheel for breaking up water or other liquid into minute particles and simultaneously mixing the atomized liquid in the 15 form of mist with air or gas, for such purposes as moistening air or washing gases.

Centrifugal fans have been commonly employed heretofore for the purposes indicated, but the power required to drive them at the 20 high speed necessary to accomplish the atomization of the water is very considerable.

In my improved drum or wheel, the blades or wings of the centrifugal fan are replaced by sheet-metal flat rings mounted parallel 25 and very near to each other and perpendicular to the axis of the drum.

It is well known that water when projected on to a rapidly rotating disk is broken up into fine particles, and it will be readily understood that in constructing a drum of a series of flat rings as described and employing means for spraying water on to these rings from the interior of the drum I provide a very effective apparatus for atomizing water. At 30 the same time a somewhat remarkable result is attained in that such a drum or wheel displaces a considerable volume of air when rotated at a high speed and this volume is increased by increasing the quantity of water 35 injected. This displacement of air, which is accomplished with a small expenditure of power, is brought about partly by the rotation of the rings but more particularly by the inductive action of the water atomized at the 40 periphery of the disks, between which the air is drawn.

Referring to the accompanying drawing, Figure 1 shows my complete apparatus, the atomizing drum being shown in longitudinal 45 section, and Fig. 2 is a cross section of the drum. Figs. 3 and 4 show in side elevation cases in which the atomizing fan is adapted to operate depending upon the use to which it is put as will hereinafter be explained.

In Fig. 1, D, D are the flat sheet-metal 50 rings. They are mounted on bars or arms

T, and the drum thus formed is mounted on a disk P which is carried by a shaft A that rotates in bearings N and is provided with a pulley M. R is a nozzle by means of which 60 water is sprayed regularly upon the rings D through the open end of the drum; this may be a simple expanding jet, as shown.

Fig. 2 shows one of the rings D. The arms T only serve to support and maintain the 65 rings in position and may be of circular or any other cross section.

Any number of rings may be connected together in the manner indicated to constitute the atomizing drum. The nearer they are to 70 each other and the greater their number, the greater will be the quantity of water which the drum will be capable of breaking up or atomizing, and the greater also will be the volume of air drawn through between the 75 rings.

My improved atomizing drum may be mounted in the free air or in a suitable chamber. Or it may be mounted in an ordinary centrifugal-fan snail-shell casing, as shown 80 in Fig. 3—in which B indicates the casing, O the eye or air-intake, and U the outlet. The same drum or wheel may also be employed for separating a gas or a vapor from dust or water carried along therewith. In this case 85 the drum is mounted in a chamber or in a snail-shell casing, but instead of allowing the air, or the gas to be washed, to circulate in the normal way, i. e. instead of the air being drawn through from the center towards the 90 circumference it is forced in by mechanical means from the back, i. e. in the opposite direction, against the current created by the rotation of the drum. Fig. 4 illustrates this application. Referring to this figure, D¹ is 95 an atomizing drum constructed in accordance with my invention mounted in a snail-shell casing B. Air is forced in by mechanical means at U and makes its exit at O; it is thus forced to pass between the flat rings 100 forming the drum from the periphery towards the center. When water is sprayed into this drum by means of a nozzle R as in Fig. 1, air forced through between the rings as indicated has to pass through a counter 105 current of mist, without being able to carry this along with it, for centrifugal force acts against it and forces the mist constantly outwards, and the apparatus thus constitutes a very effective washer and at the same time a 110 powerful separator.

It will be understood of course that when

the drum is to be used for the purposes just referred to, the rings must not be mounted too near to each other to cause an undue resistance to the passage of the counter current 5 of air.

What I claim as my invention, and desire to secure by Letters Patent, is:—

1. An apparatus for atomizing liquids comprising a rotary carriage, and supported 10 to be rotated thereby a series of rings separated from one another and parallelly arranged at right angles to the axis of their rotation.

2. An apparatus for atomizing liquids 15 comprising a rotary carriage, and supported to be rotated thereby a series of flat rings separated from one another and parallelly arranged at right angles to the axis of their rotation, said carriage being adapted in part to 20 close one end of the chamber formed within said rings.

3. An apparatus for atomizing liquids comprising a rotary disk, a series of flat rings connected therewith to be rotated 25 thereby, said rings being separated from one

another and parallelly arranged at right angles to the axis of their rotation.

4. An apparatus for atomizing liquids comprising a rotary disk, arms extending therefrom, a series of flat rings mounted upon 30 said arms to be rotated by said disk, said rings being separated from one another and parallelly arranged at right angles to the axis of their rotation.

5. Apparatus for atomizing liquids, 35 consisting of a drum made up of a number of flat rings arranged parallel to each other at right angles or perpendicular to the axis of the drum and carried by arms projecting from a disk mounted on a rotatable shaft, 40 and means for spraying liquid on to said disks substantially as set forth.

In testimony whereof I have signed my name to this specification in the presence of two subscribing witnesses.

PAUL KESTNER.
